UNITED STATES PATENT OFFICE.

WILLIAM A. DADE AND RICHARD E. MORGAN, OF ORLANDO, FLORIDA.

INSULATOR.

1,241,929.

Specification of Letters Patent.

Patented Oct. 2, 1917.

Application filed January 5, 1917. Serial No. 140,829.

To all whom it may concern:

Be it known that we, WILLIAM A. DADE and RICHARD E. MORGAN, citizens of the United States, residing at Orlando, in the 5 county of Orange and State of Florida, have invented new and useful Improvements in Insulators, of which the following is a specification.

This invention relates to improvements in 10 supporting insulators for electric current carrying wires.

In carrying out the present invention, it is our purpose to provide a supporting insulator for electric current carrying wires 15 whereby the use of tie wires and the like will be avoided, and wherein the body of the insulator will be formed with a downwardly inclined groove adapted to receive the current carrying wire, and equipped 20 with a pivoted finger arranged across the groove to prevent accidental disconnection of the wire from the insulator.

With the above and other objects in view, the invention consists in the construction, 25 combination, and arrangement of parts hereinafter set forth and falling within the scope of the claims.

In the accompanying drawings:—

Figure 1 is a view in elevation of an insulator constructed in accordance with the 30 present invention.

Fig. 2 is a similar view taken at right angles to Fig. 1.

Fig. 3 is a vertical sectional view through 35 the insulator.

Fig. 4 is a horizontal sectional view therethrough.

Fig. 5 is a detail view showing a modified form of the invention.

Fig. 6 is a perspective view of one of the 40 clips.

Referring now to the drawings in detail, 1 designates the body of the insulator. In accordance with my invention, the body 1 is 45 formed with a downwardly inclined slot or groove 2 that opens onto one side of the body and formed in the top wall of the slot or groove 2 is a channel 3 arranged at right angles to the groove. 4 designates a finger 50 arranged within the channel 3, and having the upper end pivoted upon a pin 5 extending across the channel 3 at the upper extremity of the latter and having the opposite ends thereof secured in alining openings

formed in the side walls of the channel. 55 The lower end of the finger 4 is adapted to move across the slot or groove 2 and engage a channel 6 formed in the bottom wall of the slot or groove 2.

In practice, the current carrying wire is 60 forced down into the groove 2, and in the downward movement of the current carrying wire, the finger 4 is engaged with such wire and swung into the channel 3 so that the current carrying wire may engage the 65 lower end of the slot 2. When the current carrying wire engages the lower end of the slot 2 the finger 4 is relieved of the influence of such wire and drops back to its original position, thereby closing the slot 2 70 so as to prevent the current carrying wire accidentally jumping out of such slot.

If desired, a second slot or groove may be cut into the body 1 of the insulator at right angles to the slot or groove 2 and the 75 lower end of this second slot terminates above the lower end of the slot 2. This last mentioned construction of insulator is shown in Fig. 5 of the drawings and will be found especially useful in supporting intersecting current carrying conductors. 80

In order to prevent slipping or creeping of the current carrying wire in the channel 2, we employ wire gripping members or clips 85 *a* and these clips are placed on the wire and slipped into the channel with the wire and are located in the ends of the channel, as clearly illustrated in Fig. 1 of the drawings. Each clip is formed of a length of wire 90 bent into substantially U-form, as shown in Fig. 6 of the drawings. The legs of this U-shaped clip are bent at right angles and the confronting edges thereof at the outer end are formed to provide a groove 6' and such edges, inwardly of the groove, are serrated as at 7. The serrated portions of the legs are bowed inwardly, as at 8, forming gripping jaws which firmly grip the wire when slipped into the channel 2, while the grooves 6' embrace the wire and act to hold 100 the clips on the wire when being applied to the insulator.

While we have herein shown and described the preferred form of our invention by way of illustration, we wish it to be understood that we do not limit or confine ourselves to the precise details of construction herein shown and described, as modification 105

and variation may be made within the scope of the claims and without departing from the spirit of the invention.

We claim:—

- 5 1. A supporting insulator comprising a body having an inclined wire holding slot therein open at its upper end, a wire retaining finger movable across said slot, and a two-armed wire gripping clip insertable in said slot and embodying opposed inwardly deflected and serrated portions forming wire gripping jaws, and also having convergent end portions to engage the walls of the slot whereby said jaws are caused to grip the wire.
- 10
- 15

2. The combination with an insulator having a wire receiving channel, of a clip adapted to surround that portion of the wire within the channel and formed of a single length of wire bent upon itself in substantially U-shape and having the legs bent at right angles and the confronting edges of the legs, at the outer ends, formed with grooves and with inwardly bowed serrated portions inwardly of the grooves. 20 25

In testimony whereof we affix our signatures.

W. A. DADE.
RICHARD E. MORGAN.
